UNITED STATES PATENT OFFICE

2,079,329

WATER FLUSHING DEVICE

Alexander W. Moseley, Evanston, Ill., assignor to
 Sloan Valve Company, Chicago, Ill., a corpora-
 tion of Illinois

Application July 22, 1927, Serial No. 207,622

6 Claims. (Cl. 137—69)

This invention relates to water flushing devices and has for its object to provide a new and improved device of this description. The invention has, as a further object to provide a water flushing device for water closets and the like, by means of which back siphonage of the water from the closet to the source of water supply is prevented. Under certain conditions it may sometimes happen, when flush valves are used for flushing 5 water closets that water from the flush valve brings about a condition in the pipe leading to the closet which may cause the contaminated water to flow back from the bowl through the flush valve into the water system, so as to contaminate 10 the same. The present invention has as one of its objects to prevent this backward or reverse flow of the water and thus prevent the contamination of the water system.

The invention has as a further object to provide a flushing device which will prevent objectionable noise.

The invention has as a further object to provide a flushing device which will secure a proper refilling of the bowl.

The invention has further objects which are more particularly pointed out in the accompanying description.

Referring now to the drawings, Fig. 1 is a view showing one form of flushing device embodying the invention.

Fig. 2 is an enlarged sectional view through the flush valve shown in Fig. 1.

Fig. 3 is an enlarged sectional view taken on the line 3—3 of Fig. 2.

Fig. 4 is an enlarged sectional view taken on the line 4—4 of Fig. 3.

Fig. 5 is a view showing a modified construction of device.

Fig. 6 is a vertical sectional view through the device shown in Fig. 5.

Like numerals refer to like parts throughout the several figures.

Referring now to the drawings, I have shown a flushing device consisting of a flush valve 1 connected by a pipe 2 with a source of water supply, said valve being connected by a pipe 3 with a water closet bowl 4. The flush valve 1 is arranged so that when it is operated water passes from the source of water supply through the pipe 2 and the valve 1 and is discharged by the pipe 3 into the bowl 4. It sometimes happens that the water in the pipe 3 causes a reverse flow in this pipe, due to the siphon action and thus contaminated water from the bowl is drawn up through the flush valve and enters the water

system through the pipe 2. I have illustrated certain means for preventing this result.

Referring now to Fig. 2, it will be seen that the flush valve 1 has an inlet 5 which is connected by the pipe 2 with the source of water supply. Any desired flush valve may be used and the particular flush valve illustrated in the drawings is provided with a main valve 6, which is connected with a diaphragm 7 dividing the valve into the lower chamber 8 and the upper 10 chamber 9. This main valve seats on the upper end 10 of the cylinder 11. There is an opening 12 through the main valve which is controlled by an auxiliary valve 13, shown as a tilting valve, and which is provided with an actuating device 15 consisting of the members 14 and 15, which are free to slide relatively for a portion of their length, and the actuating part 16, which engages the lower member so as to move the two members to open the auxiliary valve. The actuating part 16 is moved by a handle 17 having an enlarged end 18 enclosed in the enclosing device 19, which enlarged end engages the end 20 of the actuating part 16. A retracting spring 21 moves the actuating part and handle to their 25 initial positions when the handle is released. A by-pass is arranged between the chambers 8 and 9, so that water may flow from one to the other in order to cause the main valve to be seated. This by-pass is shown as a passageway 22 leading from the chamber 5 to the chamber 9. When the auxiliary valve 13 is tilted, the water in chamber 9 is discharged and the pressure in chamber 8 lifts the diaphragm 7 in the main valve so as to permit the water to pass from the 30 pipe 2 into the discharge pipe 3, and thence to the bowl. When the valve 13 closes water then passes from the chamber 8 through the by-pass 22 up into chamber 9, and the main valve is then closed.

It sometimes happens that the contaminated water from the bowl will pass up through the pipe 3 and into the cylinder 11 and past the auxiliary valve 13, and then through the by-pass 22 into the pipe 2 so as to contaminate the 45 water supply. In order to prevent this, I provide a siphon breaking device 23 which may be located in the valve body itself or in the discharge pipe 3, and which is arranged to prevent water remaining in the pipe 3 after the valve is flushed. 50 This device is also arranged to prevent fluid from escaping therethrough either when water is being discharged through the flush valve or because of any backward flow through the pipe 3.

As illustrated in Figs. 2 to 4, the siphon break- 55

ing device consists of a casing having an air passageway 24 therethrough, the air passageway being connected to the atmosphere outside of the pipe 3 by any suitable connection. This connection, as shown, is made by a screw 25, having a passageway 26 extending therethrough and communicating with the passageway 24. The screw 25 has a threaded engagement with the casing of the siphon breaker and a washer 27 between the casing and the inner wall of the pipe 3, and prevents leakage around the exterior of the screw. Within the casing of the siphon breaker is a closing device 28, which rests upon the removable bottom 29 of the casing and over the hole 30 in said bottom. This closing device is arranged to close the passageway 24 when there is any pressure tending to force water through the siphon breaking device. In the construction shown, the passage 24 has a narrow section 31 and the closing device has a closing piece 32 adapted to close the narrow portion 31 of the passageway when the closing piece is lifted by the pressure. The closing device is provided at its bottom with one or more openings 33, so that air or water may freely pass downwardly through the passageway 24 and out the opening 30.

In Figs. 5 and 6 I have shown a modified construction wherein the siphon breaker consists of a casing 34 having a passageway 35 therethrough and provided with a removable bottom 36 having an opening 37 therein. A screw 38 fastens the casing 34 to the casing of the valve 1 and is provided with a passageway 39 extending therethrough, communicating with the passageway 35. A washer 40 is inserted between the flush valve and the casing 34. The passageway 35 is enlarged at 41 and is provided with a closing device 42 loosely held therein. A screen 43 preferably extends across the opening 37. The enlarged portion 41 of the passageway through the casing 34 is preferably provided with an inclined inner face 44, which inclines upwardly and outwardly, thereby forming this enlarged portion 41 of the passageway of a conical shape. This construction prevents the closing device from becoming wedged in the enlarged portion 41 in the event one side should be moved up ahead of the other.

The use and operation of my invention are as follows.

When the parts are in position and it is desired to flush the closet, the handle 17 is moved in any direction. This causes the actuating piece 16 to engage the part 15 and open the auxiliary valve 13. The water in chamber 9 then escapes through the cylinder 11 and the pressure in chamber 8 lifts the main valve and permits the water to flow from the inlet 5 through the valve and out through the discharge pipe 3 into the bowl, so as to flush it. When the main valve has opened the proper amount, the auxiliary valve 13 closes so as to shut off the discharge of the water from the chamber 9. Water then flows from the chamber 8 up through the by-pass 22 into the chamber 9 and the main valve is moved to its closed position. Water discharged through pipe 3 sometimes remains in this pipe and, after the water has ceased to flow through the flush valve, it sometimes happens that this water by a siphon action, will cause the water from the bowl to be drawn up through the flush valve, past the auxiliary valve 13 and through the by-pass 22, into the main source of water supply, thereby contaminating the same. Where the

siphon-breaking device herein shown is used, this result is prevented, as air flows through the siphon breaking device into the discharge pipe 3 so as to break the vacuum therein. In Figs. 1 to 3 this air passes through the passageway 26 and the screw 25 and through the passageway 24 out through the opening 30 in the bottom 29. This prevents the back siphonage of any water from the bowl up through the flush valve. The siphon breaker must be arranged so as to prevent the leakage of fluid from the pipe 3 under all conditions, whether normal or abnormal. In order to secure this result it is desirable to have the passageway 26 through the screw properly protected so as to prevent the escape of water when the water is passing downwardly through the pipe 3, or to prevent the escape of water in the event there should be a backward flow through pipe 3 or a tendency of the water to flow through the opening 30. This result is secured by means of the casing and the closing device associated therewith.

In the construction shown in Figs. 1 to 3, the closing device 28, which is hollow and light and which may be of metal or any other suitable material, is moved under such conditions so as to close the portion 31 of the passageway 24, and thus prevent any fluid from passing out through the passageway 26.

In the construction shown in Figs. 5 and 6, the closing device 42, which may be of rubber or any other suitable material, is moved under such conditions so as to close the passageway 35.

When the present device is used water is prevented from being held or trapped in the discharge pipe and other passages and this water insures a full refill flow of water into the bowl each time the flush valve acts so that there is always provided a sufficient amount of water to insure the proper water seal in the device to be flushed.

I claim:

1. A flushing device comprising a connection leading from the source of water supply to the device to be flushed, a valve forming a part of said connection for controlling the flow of the water therethrough, a casing located on the interior of said connection and having a passageway therethrough having an upper and lower contracted portion and an enlarged portion intermediate the contracted portions, a part having a connected passageway which connects the passageway in the casing with the exterior of said connection, and a normally open closing device in said casing and located in the enlarged portion of said passageway intermediate the contracted portions adapted to close the passageway therethrough when moved upwardly to the end of the upper contracted portion so as to prevent flow of liquid through such passageway.

2. A flushing device comprising a connection leading from the source of water supply to the device to be flushed, a valve forming a part of said connection for controlling the flow of the water therethrough, a casing located in said connection and closed at the top, said casing having a passageway extending therethrough, a support connected with said casing and having a passageway therethrough communicating with the passageway in the casing.

3. A flushing device comprising a connection leading from the source of water supply to the device to be flushed, a valve forming a part of said connection for controlling the flow of the water therethrough, a casing located in said pas-

sageway between the valve and the device to be flushed and closed at the top, said casing having a passageway extending therethrough, a supporting screw extending through the wall of said connection and through the wall of said casing and having a passageway therethrough communicating with the passageway in the casing, and a closing device in said casing for closing the passageway therethrough under predetermined conditions.

4. In a flush valve, a casing having an inlet chamber and an outlet chamber, a valve controlling communication between the inlet and outlet chambers, means for causing the valve to seat automatically against the supply pressure in the inlet chamber, the casing being provided with an air vent chamber therein separate from the outlet chamber, and valve means interposed between the air vent chamber and outlet chamber for normally admitting atmospheric air to the last named chamber, said means being operative by an upward movement thereof, to close communication to the air vent chamber during the flush valve operation.
5. A flush valve device comprising a connection leading from the source of water supply to the device to be flushed, a valve forming a part of said connection for controlling the flow of

the water therethrough, a hollow part below said valve, a movable closing device therein, a contracted passageway connecting said hollow part with said connection below said valve, the closing device normally supported at the upper end 5 of said contracted passageway, the connection between the hollow part and said contracted passageway being open when the closing device is supported at the upper end thereof, the hollow part and the part containing the contracted 10 passageway being removably connected together, and a wall above said closing device having a passageway therethrough that communicates with the outside atmosphere whereby water is prevented from passing said closing device and 15 back siphonage is prevented.

6. A flushing device comprising a connection leading from the source of water supply to the device to be flushed, a valve forming a part of 20 said connection for controlling the flow of the water therethrough, a casing located in said connection between the valve and the device to be flushed and closed at the top, said casing having a passageway extending therethrough, a support connected with said casing and having a passageway therethrough communicating with the 25 passageway in the casing.

ALEXANDER W. MOSELEY.
